GOVERNOR MEANS

Alfons Ohnrich, Horni Litvinov, Czechoslovakia

Application April 11, 1935, Serial No. 15,886
In Czechoslovakia April 13, 1934

1 Claim. (Cl. 264—14)

The present invention relates to means for automatically controlling the speed of an engine or motor, more particularly an engine or motor the load of which varies considerably.

5 The object of the invention is to control the speed of the motor by regulating the supply of driving medium, for instance air or electric current in accordance with the existing load of the conveyer gutter, and it may be pointed out that 10 such conveyer gutters carry a load or charge which varies very considerably and quickly from a minimum to a maximum value, the gutter being very irregularly charged. The gutter may be charged upon its whole length or upon a portion 15 or portions of the length only, and the charging in the charged portion may differ very considerably. It will be understood that when the load upon the motor is low, the speed of the motor tends to increase excessively, whereby the 20 conveyer gutter may be subjected to excessive wear and moreover excessive and unpleasant noise may be created.

The object of the present invention is to provide an automatic control for the motor in which 25 a moving member of the motor is operatively connected with the piston of an auxiliary cylinder. In the auxiliary cylinder pressure is produced and the pressure medium produced in the auxiliary cylinder is passed into a receiving vessel provided with an adjustable outlet, and from the latter into a further auxiliary apparatus which in turn operates a valve or like means controlling the supply of the driving medium of the motor. It will be understood that the medium 30 to be compressed in the auxiliary cylinder may be either air or other fluid, or it may be a liquid, and it will also be understood that the driving medium of the motor may be a compressed fluid, for instance air, or may be an electric current, the motor to be controlled being, for instance, an air driven motor or an electro-motor.

The accompanying drawings show by way of example a construction suitable for use in connection with plant for driving a conveyer gutter by means of an air motor.

Fig. 1 is a diagrammatic plan of the complete plant.

Fig. 2 a cross section on line II—II of Fig. 1 drawn to a larger scale, illustrating a throttle valve in the supply conduit of the air motor and means for operating same.

Fig. 3 is a cross section on line III—III of Fig. 2.

Fig. 4 is a sectional elevation on line IV—IV of

Fig. 2 showing a cylinder and piston for operating the throttle valve.

Fig. 5 illustrates a modified arrangement of this invention.

Fig. 6 is a vertical sectional view along the line 6—6 of Fig. 5 showing another arrangement of the new construction for use of a liquid as auxiliary medium and showing the chief constructional part of the whole device shown itself schematically in a top view in Fig. 5.

Referring to the drawings, more particularly Fig. 1, 2 indicates an air motor, the piston rod 1 of which is operatively connected in any suitable manner with a reciprocatory conveyer gutter, not shown in the drawings. The conveyer gutter may be assumed to be connected to a forked member 3 carried by the piston rod 1. At the opposite end of the air motor is arranged an auxiliary working cylinder 4 within which works as a plunger an extended portion 5 of the piston rod 6 of the air motor 2. The cylinder 4 is provided with a suction valve 6 and with a delivery valve 7, the latter being connected by an air conduit 8 with a pressure balancing air vessel 9. The air vessel 9 is provided with an adjustable throttle valve 10 communicating with the atmosphere and with a delivery conduit 11 through which air or other pressure medium passes under pressure into a cylinder 12 (see Fig. 4) the piston 13 of which operates, by means of a piston rod 14 and transmission members 15 and 16 (see Fig. 1) a shaft 17 (see Fig. 2) carrying a valve 18, which latter is mounted in a casing 19 interposed in the main driving medium supply line 20, which, in the example illustrated, supplies compressed air to the air motor 2.

The transmission member 16 consists, in the example shown, in a lever mounted upon the shaft 17 and a helical spring 21 (Fig. 2) is provided which tends to move the shaft in the opposite direction, that is, in opposition to the piston 13. The tension of the spring 21 is made adjustable, one end 21' of the spring being for this purpose fixed in one of a series of holes 22 of a disc 23, said disc being together with the lever 16 fixedly secured to the shaft 17. The shaft 17 is mounted in anti-friction bearings 24 in order to increase the sensibility of the control device. The operation is as follows:

When the conveyer gutter is fully or normally charged, the piston of the air motor 2 performs a certain number of strokes per minute, and the plunger 5 delivers in the same unit of time from the auxiliary air cylinder 4 into the air vessel 9 a certain quantity of air under a certain pres-

sure. This pressure is continuously reduced by escape of air from the air vessel 9 through the partly opened and suitably adjusted throttle valve 10 and also by the passage of the air 5 through the conduit 11 to the cylinder 12. In the cylinder 12 the pressure of the compressed medium maintains the piston 13 in a certain intermediate position against the force of the spring 21, so that at normal load of the conveyer gutter, the control valve 19 of the main supply conduit 20 assumes a certain normal position, for instance, is completely open. If now, at any time, the conveyer gutter should be partly or entirely discharged, for instance owing to the 10 fact that there is no material along the entire length of the gutter for charging the gutter, then the air motor 2 commences to run with a higher speed and consequently owing to the increased number of strokes of the air motor, a greater 15 amount of compressed air will be forced from the cylinder 4 into the air vessel 9 so that an increased pressure will occur in the cylinder 12 and the piston 13 will be moved into a lower or the lowest position shown in Fig. 4, whereby the 20 throttle valve 19 in the main supply 20 will be closed, whilst the increased air pressure is maintained in the air vessel 9. The throttle valve 10 allows a certain amount of air to escape from the air vessel per unit of time depending on the 25 pressure in the chamber 9. By manually operating the throttle valve 10 a throttle or closing of the main supply by means of the valve 10 may also be effected.

It will be seen that the invention provides a 30 very simple means for reliably controlling the speed of one or more conveyer gutters at any time of the working operation in dependence on the load carried by the gutter, whereby undue wear of the gutter is avoided and a considerable 35 economy of driving force is attained. Moreover, the very unpleasant noise caused by accelerated running of empty or half empty gutters is entirely avoided.

It will be understood that instead of an air 40 motor a hydraulic motor might be used, the control arrangement remaining practically the same. If a liquid control medium is used instead of air, small modifications regarding the return and the drawing in of a portion of the liquid escaping 45 from the vessel 9 must be provided and in that case the liquid may also contain air.

Figs. 5 and 6 show another construction in which the auxiliary pressure medium is a liquid such as oil. In this case in a casing 30 a double-cylinder hydraulic pump is arranged which replaces the auxiliary working air cylinder 4 or 4' respectively with the piston rod 5 of the working piston of the primary mover 2, as well as the air pressure vessel 9 according to the first example of execution as described in connection with Figs. 1 to 4. Two reciprocating pistons 33 and 34 respectively are arranged in two vertical cylinders 31 and 32 of said hydraulic pump; each of said pistons contains a return valve 35 and 50 36 respectively opening upwards only and pressed down to its seating by a spring 37 or 38. At the bottom of each of both said cylinders a corresponding return valve 39 or 40 is provided which opens into the interior of the corresponding cylinder 31 or 32 and allows the liquid to enter from the common space 41 communicating freely with the large interior space 42 of the casing 30 filled with a liquid such as oil up to the level marked a.

Above the cylinders 31 and 32 a bell-shaped hollow body 43 is arranged which forms a pres-

sure chamber 44 tightly closed from the surrounding space 42 of the casing 30. Said chamber 44 may be wholly filled up with liquid, for inst. to the level marked by b. The air accumulated here may be let out from time to time 5 by the screw plug 45.

Transversely to the pressure chamber 44 the shaft 46 in tight bearings is arranged, the said shaft 46 being provided on its exterior free end with a lever 47 connected directly or by means 10 of a transmission with a moving part of the driving motor 2 (Fig. 5) or with a moving part of the conveyer gutter itself, the latter not being shown on the drawings. In the interior of the chamber 44 on this shaft 46 a double armed lever 15 48 is keyed and linked on both ends to two piston rods 49 and 50 of the above mentioned pistons 33 and 34. Both said pistons may have unequal diameters as represented on the drawings (Fig. 6) said unequal diameters corresponding to different speeds of the conveyer gutter or its motor 20 during both strokes, the downward stroke or movement of the gutter being slow and the upward one being quick for promoting the sliding action of the material loaded thereon.

The pressure chamber 44 is provided according to the new invention with a throttle valve 100 acting in the same manner as the throttle valve 10 according to the former embodiment of the present invention and serving also here for a 30 constant releasing of a certain quantity of the auxiliary pressure liquid into the free space 42 of the casing 30. The pressure chamber 44 is further in connection with the regulating device proper 19 of the main valve on the supply conduit 20 by means of a pipe 111 as described formerly.

The device as described functions as follows:

During a normal load on the conveyer gutter the driving lever 47 moves at a given rate and imparts a reciprocating motion to the double armed lever 48, a given quantity of the liquid being pressed by the pump into the pressure chamber 44. A given quantity of the liquid escapes constantly by the throttle valve 100 back into the free space 42 of the casing 30 and is sucked anew by the pistons and forced into the pressure chamber 44. The rest of the liquid forced into the pressure chamber 44 is conveyed by the pipe 111 to the controlling device 19 which throttles or releases the main valve on the supply conduit 20 of the driving motor 2.

If during a given period of the function of the system the gutter is not charged sufficiently with coal or other material so that the driving motor may overspeed, the increased action of the pump in the casing 30 immediately causes an increased output of the pump which forces a larger amount of liquid into the pressure chamber 44 from which a constant quantity of liquid escapes also in this case by the throttle valve 100, but an increased quantity of liquid is conveyed into the pipe 111, so that the regulation device 19 closes the main valve to a greater extent on the supply conduit 20.

If the conveyer gutter is overloaded the driving motor 2 runs slowly and, too, the pump in the casing 30 has a small output so that a smaller amount of the liquid is forced into the pipe 111 accompanied by the constant escaping of the liquid through the throttle valve 100; the regulation device 19 opens then the main valve to a greater extent on the supply conduit 20.

The regulation device 19 otherwise opens the main valve constantly on the conduit 20.

What I claim is:

5 A governor to control the speed of a fluid motor said motor having fluid supply means, a pump having two cylinders of unequal diameters, a pair of pistons for said cylinders, said cylinders opening into a pressure chamber at one of their ends, and valves at the other ends communicating with the reservoir, means for connecting said pistons to the fluid motor, a throttle valve for

connecting said reservoir to said pressure chamber, and means for connecting said pressure chamber to the fluid supply means of the fluid motor to control the magnitude of the output of said fluid motor in accordance with the adjustment of said throttle valve and in accordance with the operation of said pistons.

ALFONS OHNRICH.
